(57) **CLAIM**

The ornamental design for a pet feeder, as shown and described.

DESCRIPTION

FIG. 1 is a front, bottom perspective view of a pet feeder, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 2;

FIG. 10 is another perspective view of the pet feeder, shown in a position of use with an exemplary bowl;

FIG. 11 is another perspective view of the pet feeder, shown in a position of use with another exemplary bowl; and,

FIG. 12 is another perspective view of the pet feeder, shown in a position of use with an exemplary waterer.

The dash dot dash broken lines in FIGS. 2 and 9 are for the purpose of illustrating the enlarged view indicators and form no part of the claimed design. The evenly spaced broken lines are shown for the purpose of illustrating both parts of the pet feeder as well as environmental subject matters of the bowls and waterer. None of the broken lines form part of the claimed design.
